UNITED STATES PATENT OFFICE.

THOMAS T. PARKER, OF NEW YORK, N. Y.

BOILER.

1,078,212.

Specification of Letters Patent.

Patented Nov. 11, 1913.

Application filed May 28, 1913. Serial No. 770,394.

To all whom it may concern:

Be it known that I, THOMAS T. PARKER, a citizen of the United States, residing in the borough of Manhattan, city, county, and State of New York, have invented certain new and useful Improvements in Boilers, of which the following is a specification.

This invention relates to water tube boilers, particularly of the so-called horizontally inclined type or that type in which the tubes are arranged in substantially horizontal position, being usually slightly inclined upwardly at the front.

In horizontally inclined water tube boilers as now constructed there is more or less imperfect combustion of the fuel, and the products of combustion are localized or concentrated upon particular portions of the bank of tubes, principally the ends of the lower ones. This results in excessive evaporation in the tubes nearest the fire and consequent frequent renewal of same together with an uneconomical use of the fuel.

According to the present invention I provide a boiler in which a more complete combustion is obtained and in which the combustion products are distributed more equally among the tubes and evenly throughout the length thereof.

In the preferred construction of my invention I provide a boiler in which the water tubes are so arranged as to provide a secondary or supplemental combustion space or chamber above the lower level of the tubes, into which the heated gases are constrained to go before they pass in between the tubes. They are then led laterally through the various sections, preferably throughout the entire length thereof, and preferably in such manner as to cause an equal transfer of heat to the various tubes, although the relative temperatures may be controlled to secure the best results.

The invention includes various other features of improvement which will be herein-after more fully pointed out.

Referring to the drawings,—Figure 1 is a transverse section of a boiler of the double pass type, embodying the present invention. Fig. 2 is a longitudinal section of Fig. 1. Fig. 3 is a detail of Fig. 1. Fig. 4 is a transverse section of a single pass boiler, embodying the invention. Fig. 5 is a trans-

verse section, showing a modified form. Fig. 6 is a similar section of another modification.

Referring first to Figs. 1 to 3, let A indicate the boiler as a whole which is shown as mounted upon a brick foundation or frame work B. The foundation may not extend above the series of water tubes C, the outer cover of the boiler being made of metal or other suitable material. The boiler is provided with a front water box D and a rear water box E, between which the water tubes C extend. Above the rear water box E is a water drum F which is connected by a series of tubes G with the front water box D, and by a series of tubes H with the rear water box E. A complete circulation around the tubes is thus provided. The boiler is provided with a fire box I, and grate J as usual, but instead of the top of the fire box or combustion chamber being open throughout its entire area, it is partially closed by a fire-proof wall K so arranged as to provide a central opening L through which the heated gases must pass in order to reach the bank of tubes. According to the invention I provide a supplemental combustion chamber M which in its preferred form comprises a space formed by omitting a number of tubes so that the chamber will be free or substantially free of obstructions. As the products of combustion pass directly upwardly through the opening L which forms the inlet to the chamber M the gases are thoroughly mixed and a more complete combustion of the fuel is attained. In passing through the opening and into the supplemental combustion chamber the gases preferably do not strike any water cooled surfaces such as the water tubes, and the combustion which is ordinarily checked by chilling is enabled to continue until the products are substantially completely consumed. Preferably means are provided to cause a reduction of flow of gases in the combustion chamber so that a higher boiler efficiency is obtained. This may be done in several ways, as for instance by making the supplemental combustion chamber of larger cross sectional area than the chimney.

In the "double pass" type of boiler illustrated in Figs. 1 and 2, which is usually of

comparatively large size, the supplemental combustion chamber is preferably arranged in the middle of the bank of tubes so that the heated gases after passing into the chamber branch out in opposite directions and pass laterally between the tubes on either side of the chamber and are finally carried up through passages arranged along the sides of the tubes. In order to promote this lateral movement of the gases and substantially prevent their passing directly upwardly to the top of the bank of tubes, I provide below the top of the bank a wall N which is preferably of fire-proof material such as asbestos. This wall is inclined in the same direction as the bank of tubes, and effectually closes the passage of the gases at this point, constraining them to move in substantially horizontal directions toward the sides of the banks of tubes. In the double pass type illustrated I provide on each side of the bank a wall O or O' which is preferably of asbestos, and which is also preferably constructed so as to be easily removable from the tubes. To this end the wall may be provided with a hook or hooks O^2 designed to fit over one of the tubes C as best illustrated in Fig. 3. The walls O O' are formed with openings for the escape of the gases after the latter have passed through the bank of tubes. These openings are best seen in Fig. 2 at P wherein they are conventionally illustrated as oblong slots. It will be understood that the shape and distribution of these openings are so proportioned and arranged as to secure the desired flow of combustion gases through the bank or banks of tubes. In the preferred construction the proportions are such that there is an even distribution of the gases, the latter sweeping all of the tubes and pockets or dead spaces being avoided.

Upon passing through the walls O O' the gases which have given up a large proportion of their heat thence flow into vertical passages Q Q' which extend substantially the length of the tubes, and thence upwardly into the chamber R , and thence outwardly through the smoke pipe S .

According to my invention I provide a means for increasing the circulation of the boiler whereby the water is led from the front water box D to the rear water box E without circulating through the drum F . To this end I provide a series of tubes T located in the chamber K and above the top wall or baffle N , so that the tubes do not receive the direct heat from the furnace, but are out of the path of the products of combustion after the latter have passed through the bank of tubes. These tubes T which I may describe as "down comer" tubes are hence comparatively cool and form return passages for the water which are arranged

well below the water line of the boiler. 65 These tubes hence carry a large portion of the circulating water, thus permitting the tubes G , which lie at the water line of the boiler, to carry the more highly heated water and steam into the drum F . Two means 70 of circulation are hence provided, one at the water line and through the drum, and the other below the water line which connects the two water boxes directly.

It will be understood that the flow of 75 gases through the tubes and passages Q Q' or elsewhere may be controlled if desired by dampers or the like. The provision of a supplemental combustion chamber such as M also enables me to very effectively super- 80 heat the steam, if this is desired. To this end I may provide an opening such as U (Fig. 1) in the rear box E and insert a superheater therethrough, the latter prefer- 85 ably occupying a position partly in the chamber and partly in the fire box L , as indicated at V in dotted lines in Fig. 2. The necessary steam connections will be understood without further description.

In Fig. 4 I have illustrated the invention 90 as applied to a "single pass" boiler. In this type of boiler the bank of tubes is narrow laterally and the supplemental combustion chamber M' is arranged at one side as shown. In this construction there is prefer- 95 ably a series of tubes C' arranged at one side of the combustion chamber, the space between which may be filled with hollow tile, as shown at W . At the opposite side of the bank of tubes a single perforated 100 wall O^2 is provided, the construction being such that all of the products of combustion are led to the right and through the perforations in the wall.

In Fig. 5 I have shown a modified form 105 in which the wall O^2 is omitted, the products of combustion being compelled to travel into contact with the various tubes by vertically arranged baffle plates X X' X^2 , the gases finally reaching the vertical passage 110 Q^2 around the lower end of the baffle X^2 .

In Fig. 6 a similar arrangement is provided except that the baffles are angularly formed as shown at Y Y' , the gases being forced to travel upwardly into the combustion chamber M^3 , and thence in a series of 115 passes to the right and left until they reach the lower part of the vertical passage Q^2 .

In the various constructions shown the products of combustion are forced to enter 120 into the supplemental combustion chamber M , and during this process the gases are thoroughly mixed and a complete combustion takes place. A most important feature is that the heated gases are then brought 125 into contact with all of the tubes so that there are no dead spaces. A further important feature is that by the time the hot

- gases are led throughout the bank of tubes they have given up their heat to such an extent that it is unnecessary to provide brick walls around the tubes to prevent losses by 5 heat radiation. The present boiler may be constructed in more compact form than those now in use since the thorough combustion of the gases in the supplemental combustion chamber permits me to arrange the tubes 10 closer together than in other constructions wherein such chamber is omitted. In these latter constructions considerable space must be left between the tubes in order to prevent the immediate chilling of the gases to a 15 point where additional combustion is no longer possible. The construction of Figs. 1 and 2 is preferred since by this construction the gases can be brought into contact with all of the tubes, and the proper distribution 20 of the gases is easily determined and controlled by the location and size of the openings P. In all of the constructions shown the asbestos walls or baffles may be easily removed, thus creating a free passage throughout 25 the entire bank of tubes whereby the latter can be cleaned of ashes and other deposits by a steam or air jet, and whereby easy access may be obtained for replacing tubes when necessary.
- 30 It will be understood that while I have shown and described several forms of my invention I do not wish to be limited thereto, as various changes can be made therein without departing from the invention.
- 35 What I claim is:—
1. A water tube boiler having a combustion chamber, a series of substantially horizontal water tubes arranged above said combustion chamber, a supplemental combustion chamber over said combustion chamber, and a passage leading directly from said combustion chamber to said supplemental combustion chamber, said supplemental combustion chamber being bounded on at least two 40 sides by said tubes.
  2. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 45 by said tubes, and means for directing the products of combustion laterally through said series of tubes.
  3. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 50 by said tubes, and means for directing the products of combustion laterally through said series of tubes.
  4. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 55 by said tubes, a wall at the top of said combustion chamber adapted to direct the products of combustion through said passage into said supplemental combustion chamber. 60
  5. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 65 by said tubes, a wall at the top of said combustion chamber adapted to direct the products of combustion through said passage into said supplemental combustion chamber, and a wall above said series of tubes to prevent direct upward escape of said products of 70 combustion.
  6. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 75 by said tubes, a wall at the top of said combustion chamber adapted to direct the products of combustion through said passage into said supplemental combustion chamber, and a wall above said series of tubes to prevent direct upward escape of said products of 80 combustion.
  7. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 85 by said tubes, a wall at the top of said combustion chamber adapted to direct the products of combustion through said passage into said supplemental combustion chamber, and a wall above said series of tubes to prevent direct upward escape of said products of 90 combustion.
  8. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 95 by said tubes, a wall separating said tubes from said combustion chamber and directing the products of combustion into said supplemental combustion chamber through said passage, a wall above said tubes, and preventing upward escape of products of combustion, and means for controlling lateral flow of said products of 100 combustion.
  9. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 105 by said tubes, a wall separating said tubes from said combustion chamber and directing the products of combustion into said supplemental combustion chamber through said passage, a wall above said tubes, and preventing upward escape of products of combustion, and means for controlling lateral flow of said products of 110 combustion.
  10. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides 115 by said tubes, a wall separating said tubes from said combustion chamber and directing the products of combustion into said supplemental combustion chamber through said passage, a wall above said tubes, and preventing upward escape of products of combustion, and means for compelling the products of combustion to pass laterally into contact with substantially all of said tubes before they escape.
  11. A water tube boiler having a combustion chamber, a bank of substantially horizontal water tubes arranged at the top of said chamber, a number of tubes being omitted from said bank to form a supple- 120
  12. A water tube boiler having a combustion chamber, a bank of substantially horizontal water tubes arranged at the top of said chamber, a number of tubes being omitted from said bank to form a supple- 125

- mental combustion chamber within and at least partially surrounded by the tubes, and said supplemental combustion chamber being directly over and in communication with the combustion chamber, the passage between the two chambers being free from tubes whereby the products of combustion pass directly into said supplemental combustion chamber without being chilled by contact with water cooled surfaces, and combustion is completed in said supplemental combustion chamber, and means for leading the hot gases laterally into contact with the farthermost tubes and then discharging them laterally.
8. A water tube boiler having a combustion chamber, a series of substantially horizontal water tubes arranged above said combustion chamber, a supplemental combustion chamber over said combustion chamber, a passage leading directly from said combustion chamber to said supplemental combustion chamber, said supplemental combustion chamber being bounded on at least two sides by said tubes, a wall separating said tubes from said combustion chamber and directing the products of combustion into said supplemental combustion chamber through said passage, a wall above said tubes, and preventing upward escape of products of combustion, and means for controlling lateral flow of said products of combustion, and means for retarding the flow of gases through the boiler.
9. A steam boiler comprising a bank of water tubes, a front water box and a rear water box connected with said tubes, a return pipe for permitting circulation of the water, a combustion chamber arranged above the lowermost tubes and at least partially surrounded by said tubes, a wall beneath said tubes adapted to direct products of combustion into said combustion chamber, a wall above said bank of tubes and between the latter and said return pipe, and means for controlling the lateral escape of said products of combustion, said means comprising a perforated wall located at the side of said bank of tubes.
10. A steam boiler comprising a bank of water tubes, front and rear water boxes connected to said tubes, a wall above said tubes, a steam and water drum above said wall, a series of return pipes leading from said front water box to said drum, and a series of "down comer" pipes below said return pipes and connecting said water boxes directly.
11. A steam boiler comprising a bank of water tubes, front and rear water boxes, a combustion chamber within said bank of tubes, a wall below said tubes for directing products of combustion to said combustion chamber, a wall above said bank of tubes adapted to prevent direct upward escape of said products of combustion, a wall at one side of said bank of tubes, and means for separably connecting said side wall to said bank of tubes.
12. A steam boiler comprising a bank of water tubes, front and rear water boxes, a combustion chamber within said bank of tubes, a wall below said tubes for directing products of combustion to said combustion chamber, a wall above said bank of tubes adapted to prevent direct upward escape of said products of combustion, a wall at one side of said bank of tubes, and means for separably connecting said side wall to said bank of tubes, said means comprising hooks carried by said side wall and adapted to engage said tubes.
13. A steam boiler comprising a bank of water tubes, a front water box and a rear water box connected by said tubes, a combustion chamber above the lowermost tubes, a lower wall adapted to direct currents of combustion into said chamber, an upper wall adapted to prevent direct upward escape of said products of combustion, and a superheater located partly within said combustion chamber.
14. A steam boiler comprising a bank of water tubes, a number of tubes being omitted from a part of the bank to provide a combustion chamber, a fire-proof wall arranged beneath the bank of tubes and forming a passage for the products of combustion into said combustion chamber, an upper wall extending entirely across the bank of tubes, a side wall provided with perforations, said perforations being formed and located to permit escape of said products of combustion at predetermined intervals, a vertical passage beyond said side wall, a series of return pipes above said upper wall, and a chamber in which said pipes are arranged connected with said vertical passage.
15. A steam boiler comprising a combustion chamber, a bank of water tubes above said chamber, a number of tubes being omitted in the middle portion of said bank to provide a supplemental combustion chamber lying above the lowermost tubes, a bottom wall extending across the lower tubes and having a passage leading to said supplemental combustion chamber, a top wall extending entirely across the bank of tubes, and means for controlling the lateral escape of the products of combustion on each side of said bank of tubes.
16. A steam boiler comprising a bank of water tubes, a number of tubes being omitted in the middle portion of said bank to provide a supplemental combustion chamber lying above the lowermost tubes, a bottom wall extending across the lower tubes

and having a passage leading to said combustion chamber, a top wall extending entirely across the bank of tubes, and means for controlling the lateral escape of the products of combustion on each side of said bank of tubes, said means comprising perforated side walls, one on each side of said bank, and vertical passages into which said products of combustion are led through

said side walls, said vertical passages leading to a chamber above the upper wall.

In witness whereof, I have hereunto signed my name in the presence of two subscribing witnesses.

THOMAS T. PARKER.
